COLLOID MILL

Louis Gitzendanner, Richmond Hill, N. Y., assignor to Greenwich Machine & Tool Co., Inc., New York, N. Y., a corporation of New York

Application January 22, 1938, Serial No. 186,410

15 Claims. (Cl. 83—13)

The present invention relates to colloid mills of both the horizontal and vertical type, and particularly to the former.

The present application is a continuation in part of my co-pending application Ser. No. 172,833, filed November 4, 1937. It is the general object of the invention to simplify the construction, increase the efficiency and reduce the cost of this type of apparatus.

10 More particularly, it is an object of the invention to eliminate the packing which has hitherto been necessary for sealing the shaft of the rotor against the casing of the mill, thereby not only simplifying the construction but also 15 eliminating a source of frictional heat, thus reducing the power consumption, and avoiding injury to heat-sensitive fluids. Other objects and advantages of my improved apparatus will become apparent from the following, more detailed 20 description thereof.

20 I have found that in prior constructions, a packing or stuffing box about the rotor shaft was made necessary not so much by the normal pressure of the fluid fed to the colloid mill, as by the 25 peculiar phenomenon of the rebound of the liquid or paste being treated, upon striking an obstruction in its path after being centrifugally projected at the discharge end of the rotor. The 30 rotor of colloid mills, as is well known, is driven at extremely high speeds and as the liquid or paste leaves the discharge end of the rotor it has a very great momentum due to its high 35 velocity. The centrifugal force projects the liquid toward the wall of the casing and away from the shaft. However, upon striking an obstruction, 40 such as the edge of an outlet opening in the wall of the casing, the stream of liquid rebounds, a considerable part of it apparently striking the shaft at high speed. This high velocity stream exerts considerable penetrating pressure against 45 the packing, and it is for this reason that very tight stuffing boxes have hitherto been found necessary.

With the object of eliminating the necessity 50 for stuffing boxes and similar friction-producing packing, I began a series of investigations on the behavior of the liquid after it leaves the discharge end of the rapidly rotating rotor of the colloid mill. My observations have led to the conclusion that it is important to dispose a completely circular stationary path at the discharge 55 end of the rotor, so that the liquid thrown off centrifugally by the rotor meets a surface whose curvature is approximately that of the discharge end of the rotor. According to the invention,

therefore, there is provided at the discharge end of the rotor, a smooth, continuous arcuate path which gently receives the stream of discharged fluid and guides it away from the rotor. The fluid is thus caused to travel along a path which is very similar to that traversed by it just before leaving the rotor, and as this curved surface is free from irregularities or obstructions, the liquid flows smoothly therealong and is afforded no opportunity to rebound from any part thereof. 5 As it passes over the curved stationary surface, in a more or less spiral stream, its velocity is reduced, so that when it meets the edges of the outlet opening, which, according to the invention, is removed from the discharge end of the 10 rotor by such interposed arcuate path, it does not strike the edges of the opening with such violence as to rebound toward the shaft. The length of the guiding surface should preferably not be so great that the velocity of the liquid 15 flowing spirally therealong becomes insufficient to overcome the forces of gravity, for in such event the liquid would drop down from the upper parts of the surface onto the shaft.

25 The curved surface upon which the liquid discharges may take various forms. It may, for example, represent the inside surface of the housing of the mill, in which event it is desirable that the shaft be surrounded by a sleeve extending from the end wall of the housing, the 30 discharge outlet being located at such a distance from the rotor, that the free end of the sleeve lies between it and the rotor, the relationship being such that the rotary velocity of the liquid does not fall, in the interval between 35 the rotor and the free end of the sleeve, below that required to overcome the force of gravity, so that no liquid falls upon the unprotected shaft portion. The curved discharge surface may also take the form of a circular flange arranged 40 adjacent to the discharge end of the rotor and spaced from the wall of the housing. In such construction, the discharge opening can be located behind the flange and the side wall of the casing can be disposed only a short distance 45 from the free edge of the flange, thereby reducing the length of the apparatus and hence also of the rotor shaft. While the shaft may in this construction also be partly protected by a sleeve to prevent access of liquid to the bore in the 50 housing wall receiving the shaft, I have found such sleeve to be unnecessary, there being no leakage in spite of the high velocity of discharge and the absence of packing.

55 The embodiments of the invention are shown

by way of example on the accompanying drawing in which

Fig. 1 is a vertical section through a colloid mill of the horizontal type embodying the features of the present invention;

Fig. 2 represents a transverse vertical section along the line 2—2 of Fig. 1;

Fig. 3 is a partial view illustrating a modified form of the invention; and

Fig. 4 shows in elevation a view of the rotor.

Referring to the drawing, the numeral 10 represents a shaft which is driven at its right-hand end by a motor (not shown) by way of a clutch, shown generally at 11, and composed of a metallic disc 12 keyed to the shaft 10 so as to rotate therewith, and fixed against longitudinal movement thereon by means of a screw 13. The motor shaft is provided with a similar disc 14 fixed thereto. Coupling pins secured to the discs 12 and 14 pass through aligned openings in the discs and also through an intermediate leather or rubber disc 16. The construction of this clutch forms no part of the present invention and, being known, need not be described in further detail.

The shaft 11 is supported upon two ball bearings 17 and 18, the inner raceway of the bearing 17 abutting against a shoulder 19, while the inner raceway of the bearing 18 abuts against a shoulder 20 on the shaft. A lock-nut 21 on a threaded reduced portion of the shaft 10 engages the outer face of the inner raceway of the bearing 18 and secures such inner raceway against longitudinal movement relatively to the shaft. The upper raceway is clamped against a shoulder 22 provided in a sleeve 23 by means of a lock-nut 24, which is threaded into the end of sleeve 23. The lock-nut 24 surrounds the nut 21 and the reduced end of the shaft 10, but is not in engagement therewith.

The sleeve 23 forms part of or is secured to a hand-wheel 25 which is threaded into a circular bore in the supporting frame 26, as shown at 27. Upon rotation of the hand-wheel 25 in one or the other direction, the shaft 10 will be moved longitudinally for a purpose that will appear hereinafter.

The bearing 17 is free to move longitudinally within a chamber 28 provided by a casing 29 which may be bolted to the supporting frame 26, as shown at 30. The casing member 29 is provided with a disc-like wall or web 31 which has a central bore 32 through which the shaft passes. The end portion of the shaft is received within a central bore 33 in a rotor 34 of conical shape, as illustrated, the shaft being fixed to the rotor by means of a key 35. The shaft is secured to the rotor also by means of a machine screw 36 which enters a tapped hole at the end of the shaft, the head of the screw engaging against a washer 37 which bears against the end of the rotor, the screw and washer effectively closing the end of the bore 33 and preventing passage of fluid through the bore.

The rotor is surrounded by a stator 38 which, as illustrated, may form simultaneously one of the parts of the casing and may be secured to the casing member 29 in any suitable manner, as by means of bolts or screws 39a which enter tapped openings in a radial flange extending from the stator 38, the heads of the bolts or screws engaging against a similar flange on the member 29. The stator casing member 38 is provided with an extension 41 forming a receiving chamber for the fluid to be treated, such fluid being fed by a pipe

41a which is arranged in approximately the longitudinal axis of the shaft 10.

The stator is surrounded by a jacket 42 providing a chamber 43 about the stator, the chamber being adapted to receive a cooling or heating agent by way of an inlet pipe 44, the agent being withdrawn through the pipe 45. The jacket 42 may be force-fitted upon the outer surfaces of the flange 40 and extension 41, or it may be secured to the stator member 38 in any other suitable manner.

In the form of the invention illustrated in Fig. 1, the larger or discharge end of the rotor 34 is provided with a boss 38a having a plurality of radial grooves 39 running from the bore 33 to the outer surface of the rotor. Surrounding but spaced from the boss 38a is an annular flange 46 forming a horizontal extension of the stator 38. The flange 46 is spaced inwardly of the adjacent horizontal wall of the casing member 29 to provide a channel 47 which leads into an outlet 48 which opens into the channel 47 and is located radially behind the flange 46. The latter terminates a short distance from the end wall 31.

In the operation of the mill shown in Fig. 1, the fluid to be treated is charged into the chamber formed by the extension 41, whereupon it passes into the space between the rotor and stator, where the mixture composing the fluid is subjected to the desired grinding or homogenizing action. The fluid travels toward the right, at the same time acquiring a gradually increasing velocity. As it reaches the right end of the rotor, it is thrown by centrifugal force and at high velocity against the inside surface of the flange 46. Any fluid tending to spill over the edge of the rotor and move down the right end face of the rotor toward the shaft, is flung by the walls of the grooves 39, which act as impeller blades or vanes, likewise against the inside surface of the flange 46. Along this surface the fluid flows in a circular and somewhat spiral stream. When the fluid reaches the free edge of the flange, it is still traveling at high rotary speed, the speed being sufficiently great to overcome the force of gravity. The fluid then flows about the free edge of the flange and into the space 47 behind the flange, whence it passes into the outlet 48. Although the fluid may approach the outlet at quite a high velocity, and may rebound as it strikes the edges of the outlet opening, such rebounding fluid is prevented by the outer surface of the flange 46 from striking the shaft. The flange 46 thus provides a surface for receiving the discharged fluid and along which the latter travels before it reaches the outlet opening, and also a surface which prevents the fluid from falling or rebounding into contact with the shaft.

The flange 46 provides a smooth, continuous and substantially circular surface of approximately the diameter of the discharge end of the rotor. The fluid leaving the rotor thus meets with no obstruction tending to change radically its direction or speed of flow, and accordingly flows smoothly along the inside surface of the flange where its velocity is gradually reduced.

The axial length of the flange 46, or equivalent part, should be sufficiently great to cause reduction in the speed of flow of the fluid so that the fluid will not reach the outlet opening at too high a velocity; on the other hand, the flange should not be so long that the velocity of the fluid is reduced to the point where it is insufficient to

overcome the force of gravity, as then the fluid would fall onto the shaft.

Actual tests have shown that with the construction shown in Fig. 1, no leakage occurs at the bore 32 in spite of the fact that no packing is provided at this point. The absence of packing, which in prior constructions had to fit very tightly about the shaft, reduces considerably the power required to operate the mill. Whereas in prior constructions, the heat generated at the packing was often sufficient to cause destruction thereof, in the improved construction above described, there is practically no temperature rise due to friction at the shaft.

Should some leakage occur through the bore 32, as in the case of a mill which is frequently started and stopped, a certain amount of fluid then finding its way to the shaft during the idle periods, such leakage can be caught in the chamber 49 from which it may be withdrawn in any suitable way.

In the form of the invention illustrated in Fig. 3, the casing member 29 is itself shaped upon its inner surface, as indicated at 46a, to provide a smooth and continuous path, free from obstructions, for the fluid discharging at high velocity from between the rotor and stator. The fluid travels along the more or less circular surface 46a in a spiral stream until it reaches the outlet 48. This outlet is removed from the discharge end of the rotor 34 a sufficient distance to enable the speed of the fluid to be reduced to such an extent that when it strikes the edges of the outlet, it is no longer able to rebound with great violence. It is, however, desirable not to position the outlet 48 too far from the rotor, such distance becoming greater with machines operating at higher speeds, as the length of the shaft 10 is then undesirably increased. To enable the discharge outlet 48 to be located nearer to the rotor, I provide a sleeve or bushing 51 which may be cast integral with the casing member 29 and which surrounds the shaft in the region of the outlet 48. Any fluid rebounding toward the shaft thus strikes the outer surface of the bushing 51 and is prevented from working its way about the shaft 10 and into the sleeve 51. In many instances, however, the sleeve 51 is not sufficient to prevent leakage at the shaft, and in such instances, as illustrated in Fig. 3, I provide an annular deflector 52, which is arranged in the immediate vicinity of the discharge outlet 48 and causes return, toward the outlet, of any fluid which is projected thereagainst. The deflector 52 may in some cases be used alone without the bushing 51, but it will generally be best to employ a deflector in combination with the sleeve. The sleeve and deflector should terminate sufficiently in advance of the discharge outlet 48 to prevent fluid from working its way around the shaft.

The structure shown in Fig. 3 is, in principle, substantially the same as that shown in Fig. 1, the inner surface 46a in Fig. 3 corresponds to the inner surface of the flange 46 of Fig. 1; while the sleeve 51 and/or deflector 52 of Fig. 3 correspond to the rear surface of the flange 46 in Fig. 1.

As can be seen from Figs. 1 and 3, my invention presents a considerable simplification of prior colloid mill constructions, particularly as regards the manner of preventing leakage about the shaft. Also, by constructing the stator in the manner illustrated in the drawing, a very simple casing construction is secured, the casing and stator structure being made of a minimum number of parts, while the fluid to be treated is intro-

duced into the machine in a convenient and efficient manner.

The rotor and stator are preferably provided with grooves, as shown in Figs. 3 and 4. I prefer to make the distance between the grooves, i. e. the teeth, considerably longer than the diameter of the grooves. Thus, the grooves may be about $\frac{1}{8}$ inch in diameter and the teeth therebetween may be from $\frac{3}{8}$ to $1\frac{1}{2}$ inches wide at the large end of a tapered roller which is $3\frac{1}{8}$ inches long, is $2\frac{3}{4}$ inches in diameter at the large end and $1\frac{1}{2}$ inches in diameter at the small end. I prefer to make the number of grooves different in the rotor than in the stator; thus, with a rotor as just described, the stator may have three grooves more than the rotor.

It will be obvious that the most favorable dimensions for any particular size and speed of machine will depend upon the capacity of the machine, the nature of the fluid to be treated, the speed of the rotor, etc., and can be determined by simple experiment. In any case, however, care should be taken that the fluid discharging from the rotor does not meet any obstructions tending to cause rebound.

Wear at the surfaces of the rotor and stator may be compensated by a suitable operation at the hand wheel 25, such operation causing longitudinal movement of the shaft 10 toward the left. Suitable clearances are provided, as between the bearing 17, 19 and the wall 50 to allow for such movement. If desired, the discharge end of the rotor may project slightly beyond the adjacent edge of the working surface of the stator, so that when the rotor has been given its maximum adjustment for wear, the fluid discharging from the rotor will not strike any overlying grooves on the stator surface.

It may be mentioned that one of the advantages of the present invention resides in the fact that by the elimination of the necessity for a special packing about the shaft, there is avoided the necessity for providing special "Stellite" shaft sections or other wear-resisting surfaces. The shaft 10 can thus be made of ordinary material and the cost of the machine thereby reduced.

Variations from the specific design and proportions shown and described herein may be resorted to within the scope of the appended claims without departing from the spirit of the invention. Thus, in Fig. 3 a leak chamber as shown at 49 in Fig. 1, may be interposed in advance of the bearing 17, or other means may be provided for taking care of any fluid that may leak past the end wall 31.

I claim:

1. In a colloid mill, the combination of a casing, an inlet for a fluid to be treated, a stator, a shaft journalled in said casing along the axis of the stator, a rotor fixed to the shaft to rotate therewith within the stator, an annular flange extending from the stator approximately parallel to the shaft and closely about the discharge end of the rotor to receive immediately the fluid discharged by the rotor, and an outlet connected to the casing at a point spaced radially from and behind said flange.

2. In a colloid mill, the combination of a casing, an inlet for a fluid to be treated, a stator, a shaft journalled in said casing along the axis of the stator, a rotor fixed to the shaft to rotate therewith within the stator, said casing having an end wall facing the discharge end of the rotor and through which the shaft passes, there being no packing for sealing the shaft at such end wall.

an annular flange integral with the stator and extending approximately coaxially with the shaft and arranged to receive the fluid leaving the rotor at high velocity, said flange terminating a short distance from the end wall, and an outlet connected to the casing at a point approximately radially behind said flange, the treated fluid being thus compelled to flow axially beyond the flange before it can reach said outlet.

3. In a colloid mill, the combination of a casing, an inlet for a fluid to be treated, a stator, a shaft journalled in said casing along the axis of the stator, a rotor fixed to the shaft to rotate therewith within the stator, a wall extending perpendicularly to the shaft and forming part of the casing, said wall facing the discharge end of the rotor, the shaft passing loosely through said wall, an outlet leading from said casing, said casing being provided with a substantially circular surface extending approximately parallel to the shaft and arranged to receive the fluid discharged by the rotor and arranged between the discharge end of the rotor and the outlet, and with a surface lying between the discharge opening and shaft and acting to protect the shaft against impingement by fluid rebounding from the edges of the opening.

4. In a colloid mill of the horizontal type, the combination of a casing, a stator fixed to the casing, a horizontal shaft journalled in said casing along the axis of the stator, a rotor fixed to the shaft to rotate therewith within the stator, means at the discharge end of the rotor for projecting fluid flowing from between the rotor and stator outwardly toward the casing and away from the rotor-supporting shaft, said casing including an end wall facing the discharge end of the rotor and having an axial opening through which the shaft loosely passes, there being no packing about said opening, an annular flange approximately coaxial with the shaft and fixed to a stationary part at the discharge end of the rotor and radially spaced from the adjacent casing wall to receive the fluid leaving the rotor at high velocity, said flange terminating axially a short distance from the end wall, an outlet through the casing at a point behind said flange, and a collecting chamber upon the side of the end wall opposite the rotor for receiving any fluid that may leak through said opening.

5. In a colloid mill, the combination of a casing, an inlet for a fluid to be treated, a stator in the casing, a shaft journalled in said casing along the axis of the stator, a rotor fixed to the shaft to rotate therewith within the stator, means providing a substantially circular path, free from obstructions and extending substantially parallel to the shaft, immediately at the discharge end of the rotor for receiving directly the treated material as it discharges from between the rotor and stator, and an outlet arranged to receive the treated fluid after the latter has traversed said circular path, and so removed from the shaft that the fluid reaching it is unable to rebound and impinge the shaft, said means being located between the discharge end of the rotor and said outlet.

6. In a colloid mill of the horizontal type, the combination of a casing, a stator, a horizontal shaft journalled for rotation within the stator, a rotor fixed to the shaft to rotate therewith within the stator, said casing including an end wall facing the discharge end of the rotor and having an axial opening through which the shaft loosely passes, there being no stuffing box about

said opening, a flange extending approximately coaxially with the shaft in the space between the end wall and rotor and fixed to the stator at the end removed from the end wall, the other end of the flange being spaced from such end wall, 5 said flange immediately overlying the adjacent region of discharge of the fluid being treated from between the rotor and stator, and an outlet through the casing at a point behind said flange, 10 said flange being radially spaced from said outlet to provide a collecting space between itself and said outlet.

7. A colloid mill as set forth in claim 6, wherein in the vertical end face of the rotor at the discharge end thereof is provided with impeller surfaces acting to throw against the inner surface of the flange any fluid spilling over the edge of the rotor.

8. A colloid mill as set forth in claim 6 where- 20 in the discharge end face of the rotor is pro- 25 vided with a boss having radially extending grooves therein, the said grooves acting to collect fluid spilling over the discharge edge of the rotor and direct the same toward the flange.

9. In a colloid mill of the horizontal type, the combination of a casing, a stator, a horizontal shaft journalled for rotation along the axis of the stator, a rotor fixed to the shaft to rotate therewith within the stator, said casing including an end wall facing the discharge end of the rotor and arranged in proximity thereto, said end wall having an axial opening through which the shaft loosely passes, there being no packing about said opening, an annular flange approximately coaxial with the shaft and fixed to the stator at the discharge end of the rotor and forming an extension of the stator, said flange being radially spaced from the adjacent casing wall and extending to the vicinity of the casing end wall, said flange overlying the region of discharge of the fluid 30 from between the rotor and stator and receiving such fluid as it leaves the rotor at high velocity, there being a relatively narrow passageway between the free edge of the flange and the casing end wall and between the outer surface of the 35 flange and the surrounding casing wall, and an outlet through the latter casing wall at a point behind said flange.

10. A colloid mill as set forth in claim 9, where- 50 in the discharge end face of the rotor is provided with grooves acting to direct against the inside surface of the flange any fluid spilling over the edge of the rotor.

11. In a colloid mill of the horizontal type, the combination of a casing, a stator, a horizontal 55 shaft journalled for rotation along the axis of the stator, a rotor fixed to the shaft to rotate therewith within the stator, said casing including an end wall facing the discharge end of the rotor and arranged in proximity thereto, said end 60 wall having an axial opening through which the shaft passes, an annular flange approximately coaxial with the shaft and fixed to the stator at the discharge end of the rotor, said flange being radially spaced from the adjacent casing wall and 65 extending to the vicinity of the casing end wall, said flange overlying the region of discharge of the fluid from between the rotor and stator and receiving such fluid as it leaves the rotor at high 70 velocity, there being thus a relatively narrow 75 passageway between the free edge of the flange and the casing end wall and between the outer surface of the flange and the surrounding casing wall, and an outlet through the latter casing wall at a point behind said flange.

12. In a colloid mill, the combination of a casing, an inlet for a fluid to be treated, a stator, a shaft journalled in said casing along the axis of the stator, a rotor fixed to the shaft to rotate therewith within the stator, means providing a substantially circular path, free from obstructions and extending substantially parallel to the shaft immediately at the discharge end of the rotor for receiving directly the treated material as it discharges from between the rotor and stator, and an outlet arranged to receive the treated fluid after the latter has traversed said circular path, said means being arranged between the outlet and the discharge end of the rotor to shield the outlet against direct entry of fluid from between the rotor and stator.

13. In a colloid mill, the combination of a casing, an inlet for a fluid to be treated, a stator, a shaft journalled in said casing along the axis of the stator, a rotor fixed to the shaft to rotate therewith within the stator, an outlet leading from the casing, and a fixed annular member surrounding the shaft and spaced radially inwardly from the outlet, said member lying between said outlet and the discharge edge of the rotor and barring direct entry into said outlet of fluid discharging from the rotor.

14. In a colloid mill of the horizontal type, the combination of a casing, a stator, a horizontal shaft journalled for rotation within the stator, a rotor fixed to the shaft to rotate therewith within the stator, said casing including an end wall facing the discharge end of the rotor and having an axial opening through which the shaft loosely passes, there being no stuffing box about said

opening, a flange extending approximately coaxially with the shaft and fixed to the stator and immediately overlying the adjacent region of discharge of the fluid being treated from between the rotor and stator, said flange terminating axially a short distance from the end wall, and an outlet through the casing at a point behind said flange, said flange being annular in form and being throughout spaced in a radial direction from the adjacent wall of the casing and from the outlet to provide a collecting space between itself and said outlet.

15. In a colloid mill of the horizontal type, the combination of a casing, a stator, a horizontal shaft journalled for rotation within the stator, a rotor fixed to the shaft to rotate therewith within the stator, said casing including an end wall facing the discharge end of the rotor and having an axial opening through which the shaft loosely passes, there being no stuffing box about said opening, a flange extending approximately coaxially with the shaft and fixed to the stator and immediately overlying the adjacent region of discharge of the fluid being treated from between the rotor and stator, said flange terminating axially a short distance from the end wall, an outlet through the casing at a point behind said flange, said flange being radially spaced from said outlet to provide a collecting space between itself and said outlet, and a collecting chamber upon the side of the casing end wall removed from the rotor to receive any fluid that may pass through the opening in such end wall.

LOUIS GITZENDANNER. 35
